(57) CLAIM

I claim the ornamental design for a stack of flooring tiles and packaging therefor, as shown and described.

DESCRIPTION

FIG. 1 is an exploded perspective view of a stack of flooring tiles and packaging therefor, showing my new design;

FIG. 2 is a perspective view thereof, the packaging of the design omitted for clarity of illustration;

FIG. 3 is a left-side elevational view of FIG. 2, the right-side elevational view being a mirror image thereof;

FIG. 4 is a top plan view of FIG. 2, the bottom plan view being a mirror image thereof;

FIG. 5 is a front elevational view of FIG. 2, the rear elevational view being a mirror image thereof;

FIG. 6 is a perspective view thereof;

FIG. 7 is a left-side elevational view of FIG. 6, the right-side elevational view being a mirror image thereof;

FIG. 8 is a top plan view of FIG. 6, the bottom plan view being a mirror image thereof;

FIG. 9 is a front elevational view of FIG. 6, the rear elevational view being a mirror image thereof;

FIG. 10 is an exploded perspective view of an alternate embodiment of a stack of flooring tiles and packaging therefor;

FIG. 11 is a perspective view of FIG. 10;

FIG. 12 is a left-side elevational view of FIG. 10; and,

FIG. 13 is a top plan view of FIG. 10, the bottom plan view being a mirror image thereof.
